US0D1081562S

(12) **United States Design Patent** (10) **Patent No.:** **US D1,081,562 S**
(45) **Date of Patent:** **** Jul. 1, 2025**

(54) **WIRELESS CHARGER**

(71) Applicants: **Yifeng Intelligent (Shenzhen) Co., Ltd., Shenzhen (CN); ShenZhen meinuotengfei technology co., Ltd., Shenzhen (CN)**

(72) Inventor: **Gencheng Deng**, Shenzhen (CN)

(**) Term: **15 Years**

(21) Appl. No.: **29/986,660**

(22) Filed: **Jan. 18, 2025**

(51) LOC (15) Cl. **13-02**

(52) U.S. Cl.

USPC **D13/108**

(58) **Field of Classification Search**

(57) **CLAIM**

The ornamental design for a wireless charger, as shown and described.

DESCRIPTION

FIG. 1 is a left side perspective view of a wireless charger in an open state, showing my new design;

FIG. 2 is a right side perspective view in an open state thereof;

FIG. 3 is a front view in an open state thereof;

FIG. 4 is a rear view in an open state thereof;

FIG. 5 is a left side view in an open state thereof;

FIG. 6 is a right side view in an open state thereof;

FIG. 7 is a top view in an open state thereof;

FIG. 8 is a bottom view in an open state thereof;

FIG. 9 is a front perspective view in a closure state thereof, and,

FIG. 10 is a rear perspective view in a closure state thereof. The broken lines in the drawings illustrate the portions of the wireless charger, which form no part of the claimed design.

1 Claim, 10 Drawing Sheets
